UNITED STATES PATENT OFFICE.

EMILE BICK, OF BUFFALO, NEW YORK.

TOILET ARTICLE.

SPECIFICATION forming part of Letters Patent No. 684,172, dated October 8, 1901.

Application filed February 26, 1901. Serial No. 49,016. (No model.)

To all whom it may concern:

Be it known that I, EMILE BICK, a citizen of the Republic of France, residing at Buffalo, in the county of Erie and State of New York, have made certain new and useful Improvements in Hair-Brushes, of which the following is a specification.

My invention is an improvement in the class of hair-brushes which are provided with passages or pockets for holding combs.

The construction and arrangement of parts are as hereinafter described and claimed.

In the accompanying drawings, Figure 1 is a perspective view of my invention with a comb inserted in the protecting-pocket. Fig. 2 is a plan view. Fig. 3 is a central cross-section through the head of the brush, and Fig. 4 is a longitudinal section through the same.

The head A of the brush is shown circular in form, and the handle a is suitably tapered to enable it to be grasped and held with ease. Bristles b are secured in one side of the head A, and a circular mirror B is secured in a recess in the opposite side or back of the same. The back of the brush is provided with a rim or flange c, which projects beyond the face of the mirror B, as shown in Figs. 3 and 4, and thus protects the mirror from injury by contact with surfaces or other objects upon which the brush may be laid.

The brush is provided with a pocket C for receiving and holding a comb D, as shown. Such pocket C is a slot or passage formed in the head between the bristle-holder and brush-back proper and extends into the handle a a sufficient distance to accommodate a comb of moderate length. Such slot or pas-

sage C is intended to be made of such width laterally, especially between the brush-holder proper and the mirror-back, as to barely allow introduction of the comb D, so that to retain the comb in place under normal conditions I secure rubber strips e (see Fig. 4) in the outer end of the pocket C, so that the comb D is forced between them when being inserted and is then held by elastic contact therewith. The inner side of the handle a is practically in line with the back proper of the brush, and the pocket which extends into the same is of sufficient depth to allow the comb D to lie flush therein, as shown in Figs. 1 and 4, and is also accessible, so that the thumb of the hand grasping the handle a may be pressed on the comb to force it out of the other end of the pocket.

I prefer to employ a metal comb, since it can be made very thin and yet have the requisite strength.

What I claim is—

The hair-brush having a handle extended in line with its back, and a comb-pocket formed between the bristle-holder and the said back, and extending into the handle beyond the back where it is formed as an open recess adapted to receive the comb flatwise and permit access thereto, for the purpose of forcing it out of the pocket, and a rubber strip inserted in the outer end of said recess, as shown and described.

EMILE BICK.
